UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed October 8, 1924. Serial No. 742,372.

This invention relates to internal combustion engines and particularly to valve mechanism.

The valve mechanism of an internal combustion engine usually comprises poppet valves and a camshaft together with means such as tappet mechanism for operating the valve from the camshaft. The valve is usually closed by a spring and the cam operates 5 to open it against the spring action. In this mechanism there must be a slight clearance between the tappet mechanism and the valve or between the camshaft and the tappet mechanisms in order that the valve may be 10 certain to close on its seat. If this clearance is not provided the valve will "ride" and consequently will not close tightly with the result that the port will leak and the valve be burned. The horsepower of the engine will 15 also fall off due to the fact that full compression cannot be obtained.

If the tappet mechanism is adjusted for the proper clearance when the engine is cold, this clearance will sometimes be taken up 20 entirely by elongation of the valve stem when the engine gets hot. This necessitates a greater amount of clearance being provided when the motor is cold with the result that 25 this greater clearance causes a clicking action and thus makes the engine disagreeably noisy. Various means have been provided for automatically taking up this clearance or damping its action to mitigate the noise difficulty but none of these have proven entirely satisfactory due to the complication 30 involved and the inoperativeness of some of them.

One of the objects of the present invention is to provide an automatic means for taking 35 up the clearance between the valve and its operating mechanism while at the same time providing for a firm closure or seating of the valve.

Another object of the invention is to provide a clearance take-up mechanism that is retracted during each opening and closing cycle of the valve, so that the valve may be 40 insured of a firm seating.

Another object of the invention is to provide an automatic take-up for a valve mechanism together with means for positively retracting the take-up means to thereby insure firm seating of the valve.

Another object of the invention is to provide an automatic take-up means for a valve

mechanism, which means is arranged between the camshaft and the tappet mechanism.

Other objects of the invention will appear from the following description taken in connection with the drawings, which form a part of this specification, and in which:

Fig. 1 is a transverse section through an internal combustion engine embodying the invention;

Fig. 2 is a similar section showing part only of the mechanism shown in Fig. 1 and with the camshaft in a different position; and

Fig. 3 is an end elevation of the take-up device and the valve tappet.

Referring to the drawings, 10 represents an engine cylinder mounted on a crankcase 11 and having a piston 12 and a connecting rod 13. The cylinder is also provided with a cylinder port 14 which may be either an inlet or an exhaust port, and this port is closed by a poppet valve 15 of usual construction. The valve is guided in a guide 16 secured in the cylinder casting and a spring 17 yielding 50 retains the valve in closed position as shown in the drawing.

The lower end of the valve stem is indicated at 18 and this stem is operated upon to open the valve by a tappet mechanism 55 indicated generally at 19. This mechanism comprises a guide 20 mounted in the crankcase 11, a sliding tappet 21 mounted in the guide, a tappet bolt 22 threaded into the tappet for longitudinal adjustment therein, 60 and a nut 23 for locking the bolt 22 in adjusted position. A cap 24 is also provided to prevent oil from working up around the tappet 21.

In the crankcase 11 is mounted a camshaft 65 25 which is operated in the usual way from the motor crankshaft, not shown in the drawing. There is a cam 26 for each of the valves of the engine, which cams are positioned to open and close the valves on the 70 usual four-stroke cycle.

Arranged between the camshaft 25 and the tappet mechanism 19 is a rocker arm 27 which is pivoted at 28 to a bearing member 29 of the crankcase. This rocker arm bears 75 against the camshaft at the point 30 and at its outer end it is bifurcated thus forming two separated arms 31. Between these arms is mounted a dog or block 32 on a pivot pin 33 which is retained in place by a cotter pin 105 80 110

34. As shown in Fig. 2, the dog 32 is yieldingly pressed towards the right by a spring 35 arranged between a part of the arm 27 and the dog. The upper end of the dog 32 is slightly beveled as at 36 and is arranged to bear against the lower end of the tappet 21. The bevel and the spring are so arranged that the dog is yieldingly pushed in between the pivot pin 33 and the valve tappet so that 10 all clearance between these two parts is taken up and the valve tappet is lightly pressed upwardly against the lower end of the valve stem 18.

The dog 32 is also provided with a boss or 15 projection 37 between the pin 33 and the camshaft 25, which projection is so arranged that the cam 26 will strike it just as the arm 27 is riding off of the cam. This position of the camshaft is shown in Fig. 2 where it will 20 be seen that the cam has just left the contact part 30 of the arm 27 and is now touching the projection 37 of the dog 32 so that the dog has been retracted to the position shown in Fig. 2 and the tappet mechanism 25 19 is dropped down slightly to provide clearance between the tappet mechanism and the valve stem 18. This insures the firm closing of the poppet valve 18 by its spring 17. Just as soon as the cam 26 passes the projection 37 the spring 35 will act to push the dog 32 towards the right in Fig. 2 and thus wedge the tappet mechanism 19 upwardly to again take up the clearance between the tappet mechanism and the valve stem.

35. Thus it will be seen that the mechanism operates during the opening and closing cycle of the valve, to first take up the clearance between the camshaft and the valve stem and then to be automatically retracted. 40 In the form of the invention shown this taking up of the clearance occurs immediately after the cam 26 passes the projection 37 and the retraction of the dog 32 occurs just as the valve is closing and this retraction of the dog is a positive one just as the opening of the valve itself is a positive action.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the 55 spirit or scope of my invention.

Having thus described my invention, what I claim and desire to secure by Letters Patent is:

1. In an internal combustion engine, in 60 combination, a valve adapted to be opened and closed, a device for opening and closing the valve, and pivoted means between said device and the valve for taking up the clearance therebetween, said means operating 65 during the cycle to automatically move out

of engagement with the valve to insure firm seating of the valve.

2. In an internal combustion engine, in combination, a valve adapted to be opened and closed, a device for opening and closing 70 the valve, oscillatable means between said device and the valve for taking up the clearance therebetween, and means for positively freeing said take-up means from said valve during each opening and closing cycle of the 75 valve.

3. In an engine, in combination, a valve device, means for operating the valve, and a rigid pivoted take-up means yieldingly pressed between said operating means and 80 valve device.

4. In an engine, in combination, a valve device, a camshaft, and a rigid pivoted device adapted to engage the camshaft and said valve device for taking up the clearance 35 therebetween.

5. In an engine, in combination, a valve device, a camshaft, a rocker arm between the camshaft and the valve device, and a pivoted device on the rocker arm normally 90 yieldingly engaging said valve device for taking up the clearance.

6. In an engine, in combination, a valve device, means for operating the valve, and take-up means between said operating means and said valve device comprising a pivoted beveled dog.

7. In a valve operating mechanism, a pivoted arm, a dog pivoted to said arm, and a rotating cam adapted to successively 100 engage said arm and said dog.

8. In combination, a reciprocating valve, and means adapted to actuate said valve, comprising an oscillatable dog adapted to engage said valve, and a member adapted to periodically move said dog into and out of engagement with said valve.

9. In an internal combustion engine, a valve device, a valve operating means, and take-up means between the valve device and 110 the operating means comprising a pivoted member oscillatable in two directions.

10. In an internal combustion engine, a valve device, valve operating means, and take-up means between the valve device and the operating means comprising a pivoted member oscillatable in two directions in the same plane.

11. In an internal combustion engine, a valve device, a valve tappet, a cam, a rocker arm intermediate the cam and valve tappet, and take-up means comprising a member pivoted upon the rocker arm and adapted for pivotal movement upon engagement of the cam therewith.

12. In an internal combustion engine, in combination, a poppet valve, a valve tappet therefor, pivoted means for operating the valve, and means associated with said operating means and adapted to be moved into 130

and out of engagement with the tappet for operating the tappet and valve and for taking up the clearance when the valve is seated.

13. In an internal combustion engine, in combination, a poppet valve, a valve tappet therefor, pivoted means for operating the valve and means carried by said operating

means and adapted to be moved into and out of engagement with the tappet for operating the tappet and valve and for taking up the clearance when the valve is seated. ¹⁰

In testimony whereof I affix my signature.

JESSE G. VINCENT.
